UNITED STATES PATENT OFFICE

117,110

DESIGN FOR A COMBINATION STAPLING MACHINE AND TACKER

Lou Obstfeld, New York, N. Y., and John Fancher,
Chatham, N. J.

Application February 7, 1939, Serial No. 82,825

Term of patent 14 years

To all whom it may concern:

Be it known that we, Lou Obstfeld and John Fancher, both citizens of the United States and residents, respectively, of the city of New York, in the county of Kings and State of New York, and of the city of Chatham, in the county of Morris and State of New Jersey, have invented a new, original, and ornamental Design for a Combination Stapling Machine and Tacker, of which the following is a specification, reference being had to the accompanying drawing, constituting a part thereof.

The figure is a perspective view of the combination stapling machine and tacker showing our new design.

We claim:

The ornamental design for a combination stapling machine and tacker, substantially as shown.

LOU OBSTFELD.
JOHN FANCHER.
